UNITED STATES PATENT OFFICE.

MAX KRUSE, OF CRESWELL, OREGON.

SAW OILER.

Application filed February 4, 1926. Serial No. 86,033.

This invention relates to an improvement in saw oilers especially adapted for use by lumber fallers and buckers.

In sawing down trees and in sawing the felled trees into logs, pitch is often encountered, and in order to saw effectively, kerosene must be continuously applied to the saw blade.

The object of the present invention is to provide a saw oiler adapted for these purposes and which when used by buckers simultaneously oils both faces of the saw in an effective manner and without waste of the lubricant.

15 A further object is to provide a novel form of mounting or hanger for the saw oiler.

Other objects and advantages reside in certain novel features of the construction, arrangement and combination of parts which will be hereinafter more fully described and particularly pointed out in the appended claims, reference being had to the accompanying drawings forming a part of this specification, and in which:

25 Figure 1 is a perspective view showing the invention in use when sawing down a tree.

Figure 2 is a view partly in vertical section and partly in elevation showing the oiler embodying the invention.

30 Figure 3 is a fragmentary view in side elevation showing the oiler in use in oiling a saw when cutting a felled tree up into logs, and

Figure 4 is a sectional view on the line 35 4-4 of Figure 3.

Figure 5 is a rear elevation of the can with holder applied.

Referring to the drawings it will be seen that in all embodiments of the invention the oiler comprises a cylindrical container 1 having a head 2 closing its upper end, the head 2 being provided with a threaded filling neck 3 to which a cap 4 is applied. The cap 4 preferably has a vent 5. The lower end of the container 1 is provided with a lower head 6 terminating in a threaded filling head 7 with which a cap 8 is engaged. The cap 8 has a discharge fitting connected thereto, the discharge fitting preferably consisting of an outlet cock or spigot 9 having an externally threaded nipple 10 extended through the cap 8 and clamped thereto by a nut 11. In the cock 9 a turning valve plug 12 is fitted and held and has a bore or opening adapted 55 to be aligned with the bore or opening of the cock or to be moved out of registry therewith

whereby to permit or shut off the flow of oil or lubricant. By permitting partial registration of the bore of the plug 12 with the bore of the cock 9 to a greater or lesser degree 60 the flow may be regulated. The body of the cock 9 is provided with a discharge tip 15 having an axial passage 16 terminating in an axial discharge port and communicating with lateral ports 17. With this arrangement of ports a number of flexible and absorbent lubricant applicators are organized, the lubricant applicators being designated at 18 and 19 and preferably consisting of cords extended through the lateral ports 17 65 and out through the axial port of the passage 16, the cords having knots 18^a and 19^a therein to prevent their accidental displacement.

A hanger is provided for the saw oiler 75 constituting the present invention and consists of a yoke 20 embracing the neck at the lower end of the container and extending through a loop 21 fastened to the head 6. The arms of the yoke are designated at 22 and 80 these arms extend longitudinally of the container at one side thereof and gradually converge so that at a point adjacent the upper end of the container these arms merge together, as indicated at 23, and are welded or 85 soldered together and constitute the shank 24 of a hanger hook, designated generally at 25. The shank 24 is held to the container by means of a strap 26 having its ends fastened to the container and embracing the shank of 90 the hook.

With this arrangement the container may be supported to oil the saw used in cutting down a tree as illustrated in Figure 3 or may be used in oiling a saw employed in cutting 95 up a felled tree into logs. In the latter use the lubricant applicators 18 and 19 extend down across the opposite faces of the saw and effectively apply lubricant thereto. Notwithstanding the vertical disposition of 100 the sawing blade, as indicated, the present invention is adapted for use in oiling a saw for all purposes but is especially effective in applying kerosene to the saw blades in order to carry out the sawing operation when pitch 105 is encountered.

I claim:

1. A saw oiler for use on logs and trees and comprising a container having a reduced neck at its lower end provided with a discharge fitting and a hanger having a yoke embracing the neck, said yoke having arms 110

extending up along the container and converging in a single member terminating in a hook above the container, means for securing the yoke to the lower end of the container, and means for securing the hanger to the container above the point where its arms merge into the single member.

2. A saw oiler having a discharge fitting provided with an axial discharge passage and also having opposed lateral ports, and flexible and absorbent lubricant applicators extended in through the lateral ports and out through the axial discharge passage.

3. A saw oiler having a discharge fitting

provided with an axial discharge passage 15 and also having opposed lateral ports and flexible and absorbent lubricant applying cords extended in through the lateral ports and out through the axial discharge passage, the cords being knotted to prevent their displacement.

4. A saw oiler comprising a container having a discharge port, two flexible and absorbent lubricant applicators, each having an end secured in the said discharge port 25 and the other end free, whereby they may contact with opposite sides of a saw.

MAX KRUSE.
